COLLAPSIBLE TUBE AND KEY AND REST
FOR SAME

Alexander Bruzaud, New York, N. Y.

Application December 3, 1935, Serial No. 52,662

10 Claims. (Cl. 221—60)

My invention concerns a key used for exuding the contents of a collapsible tube.

The preferred way of squeezing out a paste or plastic contained in a collapsible tube is to displace the contents of the tube from the bottom up; as the contents of the tube are thus dispensed, the bottom end of the tube is pressed flat; and the flattened part is rolled or folded up, step by step, until the tube is empty.

10. My invention is an implement for rolling the collapsible tube up from the bottom; but at the same time it provides a rest or stand for supporting a collapsible tube in substantially upright position.

15. I shape the key of my invention, so that it may readily be attached to a collapsible tube. Due to purely commercial considerations, but also as a cautionary measure, I may provide keys which fit only one tube or one kind of collapsible tubes.

20. In contradistinction to the prior art, in which the base edge of the collapsible tube is straight, such special adaptation in true key fashion involves an irregular shape of the bottom edge of 25 the collapsible tube; i. e. said edge is curved, e. g. offset in zig-zag formation, in conformity and for cooperation with a so-called crank formation of the key. Thus I impart to the flattened bottom end of a collapsible tube a three-dimensional aspect, which entails structural rigidity; the value of such departure is enhanced in conjunction with another object mentioned below, according to which my key serves as a rest supporting the tube in an upright position. Where- 30 as the prior art required that the upright portion of the tube was more or less tightly filled in order to stand erect, my introduction of an appreciable third dimension at the very base of the tube causes structural reinforcement and ob- 35 viates continuous, tight jamming of the key.

40. Thus the tube will readily remain erect although the key is not turned except at comparatively large angles, e. g. about 72°.

Besides, since no jamming is necessary, a tube 45 of my construction is tensioned very little during use; and collapsible tubes notoriously have a limited tensile strength.

50. It is an object of this invention that the key, after it has been affixed to a collapsible tube, exudes contents of the tube with only the slightest exertion; that the key may be manipulated as easily from one side of the tube as from the other; that there is clearance for manipulation; and that the key is guided upon the tube in such 55 a way that it will roll up the tube straight, even

though the operator has been careless and has started winding the key at a slant.

Together with these and further objects which will be understood from the following description, the outstanding objects of this invention 5 resides in the conversion of the key for a support allowing the tube to stand upright, or stand erect at a slight incline, when not in actual use. An upright position is convenient for handling the tube and from the standpoint of neatness, 10 it involves economy in the space occupied by the tube, and it facilitates the election of a desired tube among a number of stored tubes.

A key of my invention is extremely simple and merely comprises two substantially pentagonal 15 or radially spoked handles, which are secured upon opposite sides of a collapsible tube. At the same time they may be spacedly interconnected, e. g., by an arbor, to which the lower end of a collapsible tube may be readily attached, and 20 upon which it may be wound or rolled up.

The feature of reinforcement allows large angular steps in winding my key. Still I prefer to have the positions of rest spaced apart to less than a right angle, thus facilitating the setting up of the key at conveniently angular positions. The fact that the flanges are flared away from each other facilitates manipulation 25 of the key of my invention.

Thus my invention represents a very simple 30 device, but also a clear departure from the old art and it may be executed in many different ways. In order to render a clear description of my invention, I explain in the following one specific example of my invention in detail; it is 35 however understood that this specific description is purely illustrative and is not rendered by way of limitation.

In the accompanying drawing:—

Fig. 1 shows a collapsible tube partly rolled 40 up upon a key of my invention in a side view.

Fig. 2 shows the key in a top view.

Fig. 3 shows a key in a perspective side view, ready to receive and support a tube C; note the exemplary modification in the crank formation 45 as compared with Fig. 2.

Fig. 4 shows a partly sectioned side view of a key of my invention, which is exemplarily integral and moulded, e. g., a die casting. A bulge B as a hub provides for distribution of the material in the manufacture.

Figs. 5 and 6 refer to modified integral executions of my key:

Fig. 5 is a blank stamping.

Fig. 6 shows a partly finished view of one end 55

of the key; the shaped arbor 11 is in the process of being bent up, whereas the broken lines indicate the final position of the arbor and the finished article, into which the blank of Fig. 5 5 is bent. The flanges may be additionally secured upon the arbor, e. g. by spot welds at A. Within the knowledge of those versed in the mechanical arts, the parts may of course be completely brazed or welded together.

10 Fig. 7 shows the irregular edge E, which I provide on a collapsible tube C, said tube being here shown in an end view. Such a tube stands erect in a key of my invention.

15 Similar numerals refer to similar parts throughout the various views.

The apices of the preferably conical handles or flanges 16 of the keys of Figs. 1, 2 and 3 are interconnected, as hubs, by the arbors 11. From the ends of the arbors may extend tongues or 20 spikes 17 which fit through perforations in the hubs of the flanges 16, and which are turned over, so that the flanges are aligned with each other in parallelism to the arbor.

In a manner well known to those acquainted 25 with this art, the arbor 11 may of course also be integral with the flanges 16, e. g., shaped out of the material of the flanges and bent normal thereto, as shown in Figs. 5 and 6. The bent-up arbor may be suitably secured, e. g., by spot weld 30 A, upon the flanges.

Likewise, instead of being built up from flat stock, the key may of course be cast or molded in any suitable material, and with modified profiles, again with integral arbor and flanges as taught 35 by Fig. 4.

The arbor 11 may have any preferred shape, e. g., it may be bifurcated, for engaging upon 40 the base of collapsible tubes. For the purpose of my example I have chosen a U-shaped cross-section, with a longitudinal slot 12, so that the tube may be set into the trough-like arbor. If the implement of my invention is to work in true key fashion so that it fits one tube only, or one type of tubes, the arbor is curved as indicated in Fig. 45 2, and in the modification of Fig. 3. Of course these are only exemplary selections of a great many configurations of specific bit-type key; it is however desirable that the eccentricity caused by curving the arbor at one point, e. g. 21, in one 50 direction, be offset by curving it elsewhere, e. g. at 22, to the same extent in the opposite direction, in relation to the axis around which the key of my invention is rotated in crank fashion.

The flanges of the key of my invention may be 55 executed in many different materials as well as polygonal shapes (e. g. spoked, webbed, or solid); likewise I am not limited in respect to the number of corners I provide on the flanges, except within the considerations of my introductory remarks; it 60 is however understood that the distance between adjacent corners determines the spread of these corners as legs of the support, which purpose the key of my invention serves in connection with the collapsible tube mounted thereon. On the 65 other hand, in order to provide multi-cornered flanges, which will stand in support of the collapsible tube at substantially any position into which the said tube is wound onto the arbor of the key, 5 corners are provided for in the drawings.

70 For the sake of stability I prefer to give the flanges a shortest diameter larger than the diameter of the tube they are applied to.

In the drawing the corners of the flanges are 75 at the ends of wings of radial handle spokes 14

extending from central hubs. These are preferably attenuated to points 10, obviously in consideration of the spread desired when the key serves as a support or leg.

The flanges 16 are oppositely flared out, being 5 convex where they face each other, so that they clear the body of the tube, and may readily be manipulated. At the same time the inwardly convex, conical or pyramidal flanges serve to align the arbor in a direction normal to the ex- 10 tent of the tube, to which the key is attached.

It is evident to anybody acquainted with this art, that a key of my invention may be made a part of any collapsible tube, or that the flanges thereof may be permanently or detachably aligned 15 upon the sides (e. g. the ends of the reinforced bottom edge) of a collapsible tube.

What I claim is:

1. In combination with a collapsible tube, a key and rest for said tube comprising a winding arbor, 20 multicornered flanges symmetrically arranged upon opposite sides of said arbor and serving for manipulation of said arbor, said flanges being outwardly flared away from each other, so that they extend clear of a collapsible tube, when 25 such tube is wound on said arbor.

2. In combination with a collapsible tube, a key and rest for said tube comprising a multi-cornered conical flange, the corners of said flange being disposed at the periphery of the base of 30 the cone, the flange extending substantially in the conical surface of such a cone, a winding arbor, and a hub at the apex of said flange and engaged upon one side of said arbor, said flange serving for manipulating said arbor, when a 35 collapsible tube is to be wound thereon.

3. In combination with a collapsible tube, a key and rest for said tube comprising a multi-cornered conical flange, the corners of said flange being disposed at the periphery of the base of the 40 cone, the flange extending substantially in the conical surface of such a cone, a winding arbor, and a hub at the apex of said flange and engaged upon one side of said arbor, said arbor extending away from the cone of said flange, said flange 45 serving for manipulating said arbor, when a collapsible tube is to be wound thereon.

4. In combination with a collapsible tube, a key and rest for said tube comprising multicornered conical flanges, the corners of each flange being 50 disposed at the periphery of the base of the cone, each flange extending substantially in the conical surface of such a cone, a winding arbor, and hubs at the apices of said flanges and mounted on opposite sides of said arbor so that said conical 55 flanges flare away from each other for ready manipulation alongside of a tube wound on said arbor.

5. A key and rest for a collapsible tube comprising a winding arbor, flanges spaced apart by 60 said arbor, one of said flanges being multicornered and outwardly flared away from the other in pyramid fashion, so that said flange extends away from a collapsible tube wound on said tube and may thus be readily manipulated. 65

6. A key and rest for a collapsible tube comprising a winding arbor, multicornered flanges spaced apart by said arbor, one of said flanges being outwardly flared away from the other and substantially forming the outline of a pyramid, 70 so that said flange extends away from a collapsible tube wound on said tube and may thus be readily manipulated.

7. A key and rest for a collapsible tube comprising a winding arbor, multicornered flanges 75

spaced apart by said arbor, said flanges being symmetrically outwardly flared away from each other in the outlines of pyramids, respectively, so as to provide manipulating clearance when a collapsible tube is wound on said arbor between said flanges.

5. In a key and rest for a collapsible tube, a winding arbor eccentrically offset intermediate its ends in crank shaft fashion, and flanges at 10 the ends of said arbor serving for a rest when a collapsible tube is mounted on the arbor, and for winding manipulation of the arbor.

10. In a key and rest for a collapsible tube, a

winding arbor eccentrically offset intermediate its ends in crank shaft fashion in opposite directions, and flanges at the ends of said arbor serving for a rest when a collapsible tube is mounted on the arbor, and for winding manipulation of the arbor. 5

10. In a key and rest for a collapsible tube, sets of handle spokes serving as legs and for key manipulation, and a winding arbor interconnecting said sets and shaped to support and kinked where it supports said tube, so that there are 10 longitudinal reinforcing folds in said tube when it is mounted on said key and rest.

LEXANDER BRUZAUD.
